APPARATUS FOR FINISHING REFLECTOR BLANKS

Filed June 5, 1922

FIG.1.

Patented Feb. 9, 1926.

1,572,451

UNITED STATES PATENT OFFICE.

WILLIAM H. TAYLOR, OF FORD CITY, PENNSYLVANIA, ASSIGNEE TO PITTSBURGH PLATE GLASS COMPANY, A CORPORATION OF PENNSYLVANIA.

APPARATUS FOR FINISHING REFLECTOR BLANKS.

Application filed June 5, 1922. Serial No. 566,202.

To all whom it may concern:

Be it known that I, WILLIAM H. TAYLOR, a citizen of the United States, and a resident of Ford City, in the county of Armstrong and State of Pennsylvania, have made a new and useful Invention in Improvements in Apparatus for Finishing Reflector Blanks, of which the following is a specification.

The invention relates to apparatus for finishing the glass reflector blanks and particularly the large sizes employed running up to sixty inches or more in diameter. These blanks have the usual sharp corners incident to cutting the blank to circular form preliminary to bending and it becomes necessary to finish these edges by beveling off the corners and smoothing and truing up the edges so that the glass has a uniform diameter throughout. In some cases the finishing operation also calls for the cutting of a hole several inches in diameter centrally of the reflector. The invention has for its principal objects the provision of improved means for accomplishing the above operations simultaneously, at a small expense and without danger of breaking or chipping the glass. It will be understood that while the apparatus is designed primarily for use upon large reflector blanks, the invention is not limited to use in such connection, and that it comprehends all uses of the apparatus as a whole or in part where similar functions are accomplished. One embodiment of the invention is illustrated in the accompanying drawings wherein:

Figure 1 is a vertical section through the apparatus with the parts in position of use; Fig. 2 is an enlarged detailed section through the device for cutting the opening through the central portion of the glass blank; Fig. 3 is a plan view of the apparatus on a reduced scale to show the relative location of the three edge finishing discs or wheels; Fig. 4 is an enlarged section on the line IV—IV of Fig. 3; and Fig 5 is an enlarged section through the lower edge of the blank after the edge has been finished by the three sets of grinding wheels.

Referring to Fig. 1, the glass blank 1 which is to be finished is carried by the table or support 2, to which it is secured by a layer 3 of adhesive material, such as pitch, which holds the glass very securely after it has hardened. The table is rotated by means of the axle or shaft 4, having a suit-

able thrust bearing 5 at its lower end and a pair of other bearings 6 and 7 carried upon the framework 8. Intermediate the two bearings 6 and 7 is a pulley 9 which is keyed to the shaft and driven from the belt 10.

Carried by the framework 8 and spaced around the periphery of the table at substantially equal distances are the brackets 11, 12 and 13 which act as supports for the three grinding wheels 14, 15 and 16. The grinding wheels are made of suitable abrasive or cutting material, such as stone or composition, and are designed to cut the three surfaces 17, 18 and 19, shown on an enlarged scale in Fig. 5, the wheel 14 cutting the bevel 17, the wheel 15, the bevel 18 and the wheel 16 the surface 19. As will be seen by reference to Figs. 1 and 4, the wheels and their supporting means are of similar construction, the only difference being that they lie at different angles with respect to the edge of the blank in order to cut the three different surfaces. A detailed description, therefore, of one will be sufficient to indicate the construction of the other two. Using the wheel 14 for the purpose of this description, this wheel is mounted upon an axle 20 and has its central portion cut away, as indicated at 21^a. The axle 20 is carried by a suitable bearing in the arm 21, such arm being pivoted to the bracket 11 upon the axis 22. The wheel is normally pressed forward, so that its face engages the edge of the glass by means of the spring 23 whose tension may be adjusted by means of the threaded member 23^a extending through the lower end of the arm 21. The forward movement of the arm 21 is limited by means of the screw member 24 which is threaded through the arm and is adapted to engage the projection 25 on the bracket 11 after the arm has been fed forward the distance necessary to cut the bevel 17.

The center line 26 of the wheel 14 is located off center with respect to the point of contact 27 between the edge of the glass blank and the wheel so that the rotation of the glass blank causes a rotation of the grinding wheel. The distance which the center line 26 is off center with respect to the line of grinding contact is relatively slight, however, so that the rotation of the wheel 14 is quite slow. The other grinding wheels 15 and 16 are similarly mounted upon arms 28 and 29 and the relation of the

wheels to the line of grinding contact is similar to that above set forth with respect to the wheel 14. The use of the springs 23 serves to give the necessary grinding contact between the wheels and the edge of the blank, which grinding pressure is heaviest at the beginning of the operation and gradually decreases as the grinding progresses, the extent of grinding being determined by 5
10 the adjustable stop devices 24. The decreasing pressure as the grinding progresses is advantageous as the decreased pressure gives a finer grinding finish and the surface produced is better than if the same relatively 15 high grinding pressure were maintained throughout the operation.

In order to cut the opening through the center of the glass while the edge finishing operation is in progress, the cutting cylinder 30, shown in detail in Fig. 2, is employed. This cylinder is carried by a transverse bar 31 upon which the device is supported by means of the spindle 32. The cylinder 30 is preferably of copper and is bolted 20 to a cast iron ring 33 which is provided at its center with the ball socket 34 adapted to receive the ball 35 at the lower end of the spindle 32, the screw sleeve 36 serves to hold the ball in position in the socket. The 25 spindle 32 slides freely in a vertical direction through the boss 37 carried by the bar 31, but is prevented from rotating by means of the key 38. In order to prevent the rotation of the cylinder 30, the interengaging 30 pins 39 and 40 are employed, the pin 39 being secured in the spindle 32 and the pin 40 being secured in the ring member 33.

In order to make the lower edge of the copper cylinder 30 effective as a glass cutter, such edge is charged with a hard abrasive powder, such as diamond dust. This is accomplished by means of a small hammer, the dust being scattered over the edge of the cylinder and pounded into the relatively 40 soft metal by means of the hammer. A cutter so charged with an abrasive powder will serve to cut a number of holes without recharging the edge with the diamond dust. After the edge becomes ineffective as a cutter, it can be recharged. The action of this 45 annular cutting device is such that by the time the grinding wheels have finished the edge of the blank, the annular cutter has

cut its way through the glass. In operation the cylinder cuts by reason of its weight, settling down into the glass as it cuts, this being permitted by reason of the mounting of the axle or spindle 32 to move freely in the supporting bar 31. The universal mounting by use of the ball and socket joint permits the cutter to adjust itself to the groove cut and avoids any tendency to bind. The action of the cutter is rapid and clean and the walls of the hole which is cut are smooth and straight and not tapered as is the case where carborundum cutting is employed. The cylinder has been employed in cutting openings as high as 13" in diameter and the metal cylinder employed in such case is preferably about 2" high and 70 $1\frac{1}{8}$ " thick.

What I claim is:

1. In combination in apparatus for finishing circular glass blanks, a table or support, means for securing the blank to be finished to such table or support, idler grinding wheels arranged around the periphery of the table with their faces in position to engage the edge of the blank and at varying angles with respect to said edge, a cutting cylinder with its axis concentric with that of the table or support with its lower edge engaging the glass and held against rotation, and means for rotating the table or support to move the glass blank relative to the said wheels and cylinder and so secure a cutting action thereon.

2. In combination in apparatus for finishing circular glass blanks, a table or support, means for securing the blank to be finished to such table or support, idler grinding devices arranged around the periphery of the table or support, means causing such devices to press against the edge of the blank, an annular cutter with its axis concentric with the axis of the table or support engaging the surface of the glass, and means for causing the table and grinding devices and cutter to rotate relatively to secure a cutting action between said grinding devices and annular cutter, and the glass blank.

In testimony whereof, I have hereunto subscribed my name this 1st day of June, 1922

WM. H. TAYLOR,
